UNITED STATES PATENT OFFICE.

JAMES S. SMYSER, OF HARWICH, MASSACHUSETTS, ASSIGNOR TO GENERAL ELECTRIC COMPANY, A CORPORATION OF NEW YORK.

ELECTRIC FLUID-HEATER.

No. 905,597.

Specification of Letters Patent.

Patented Dec. 1, 1908.

Application filed April 4, 1908. Serial No. 425,088.

To all whom it may concern:

Be it known that I, JAMES S. SMYSER, a citizen of the United States, residing at Harwich, county of Barnstable, State of Massachusetts, have invented certain new and useful Improvements in Electric Fluid-Heaters, of which the following is a specification.

This invention relates to electric fluid heaters and has for its object the provision 10 of a device of this character in which the fluid may be heated to any desired temperature in a simple and efficient manner.

More specifically my invention relates to what are known as electrolytic heaters in 15 which the fluid is heated directly by the current, that is, the fluid forms a part of the electric circuit.

In carrying out my invention the two electrodes between which the fluid is heated 20 are made in similar form adapted to mesh with each other so as to leave a narrow space for the fluid. By this arrangement a large area of contact is presented and a very compact heater produced.

25 In the accompanying drawing in which I have shown my invention embodied in concrete form, Figure 1 is a sectional elevation of my device; Fig. 2 is a cross-section of the same, the cover being removed; and Figs. 30 3, 4 and 5 are plan views of modified forms of the heating unit.

Referring to the drawing 10 represents a receptacle preferably of metal and circular 35 in form having an insulating lining 11. Within this receptacle are arranged the electrodes between which the fluid is to be heated. These electrodes 12 and 13 are preferably similar in shape, each consisting of a plurality of plates 14 and 15 arranged parallel 40 with each other and spaced apart so as to allow the fluid, such as water, to pass between them. Plates 14 are all arranged in multiple by being connected together at one end by means of a segmental plate 16 and the plates 15 are similarly connected together 45 at their opposite ends by means of the segment 17, a space being left between the ends of the plates of one electrode and the segment of the other. In this way the 50 two electrodes while being very close together are out of contact with each other and present a very large conducting surface inclosed within a comparatively small space. The electrodes are mounted within the receptacle by being secured to but insulated 55

from the cover 18. Binding screws 19 and 20 are tapped into the segmental plates 16 and 12 respectively and are insulated from the cover by means of the insulating sleeves 21. Pipe connections 22 and 23 are arranged 60 at the upper and lower end of the receptacle respectively, for circulating the fluid, such as water, between the electrodes.

In Fig. 3 I have shown another form of the electrode in which the plates 24 instead 65 of being flat are circular in form being joined in the center by a yoke 25. In Fig. 4 a similar result is effected by having the plates 26 and 27 of helical form adjacent each other and spaced apart, while in Fig. 70 5 the same result is obtained by having the connecting yokes 28 and 29 straight instead of circular as shown in Fig. 2.

It will thus be seen that I have provided an electrolytic heater which is an exceedingly compact structure and in which a large conducting surface is obtained in a simple manner. The numerous channels for liquid flow insure a large delivery of hot liquid and the structure admits of a very 80 small gap between electrodes without interfering with volume of liquid supply.

While I have described my invention in connection with a specific structure and combination of parts it should be understood 85 that I do not limit my invention thereto except in so far as it is limited by the scope of the claims annexed hereto.

What I claim as new and desire to secure by Letters Patent of the United States, is,— 90

1. An electric heater comprising a plurality of spaced parallel plates, the alternate ones being connected in multiple to form opposite electrodes, and means for maintaining a fluid between the electrodes to complete 95 a circuit.

2. An electric heater comprising a fluid receptacle, a pair of electrodes adjacently mounted therein each composed of parallel spaced plates connected at one end, and circuit terminals for said electrodes. 100

3. An electric heater comprising a fluid receptacle, a pair of similarly shaped electrodes mounted therein and arranged to mesh with each other but spaced apart, and circuit terminals for said electrodes. 105

4. An electric heater comprising a fluid receptacle, a pair of similarly shaped electrodes mounted therein each having its conducting surface arranged in parallel planes 110.

said electrodes being meshed together but out of contact with each other, and circuit terminals for said electrodes.

5. An electric heater comprising oppositely arranged groups of spaced parallel plates connected in multiple, the plates of one group alternating with those of the other group, circuit connections through said

plates, and means for causing fluid to flow between the plates to complete the circuit. 10

In witness whereof, I have hereunto set my hand this second day of April, 1908.

JAMES S. SMYSER.
